UNITED STATES PATENT OFFICE.

JOHN M. PEDERSON, OF NOME, NORTH DAKOTA.

BOARD-PULLING TOOL.

1,415,693.

Specification of Letters Patent.

Patented May 9, 1922.

Application filed May 23, 1921. Serial No. 471,540.

To all whom it may concern:

Be it known that JOHN M. PEDERSON, a citizen of the United States of America, residing at Nome, in the county of Barnes 5 and State of North Dakota, has invented new and useful Improvements in Board-Pulling Tools, of which the following is a specification.

The object of the invention is to provide 10 a simple and efficient means, affording a considerable leverage for detaching or stripping flooring, roofing and siding board and the like from the scantling, joists, studding and the like and for removing the spikes or 15 nails by which such boards, strips and like objects are secured to the framing timbers, under conditions imposing the minimum effort upon the operator and involving the minimum risk of mutilating, breaking, splitting, 20 or otherwise rendering the timber unfit for subsequent use; and with this object in view the invention consists in a construction and combination of parts of which a preferred embodiment is shown in the accompanying 25 drawings, wherein:

Figure 1 is a view in perspective of the tool.

Figure 2 is a side view of the same.

Figure 3 is a vertical sectional view of 30 the angle of the tool.

The apparatus consists essentially of an operating lever 10 forming a handle and provided at one end with a foot 11 preferably formed as an extension of the lever substantially at right angles thereto, and a claw head 12 pivotally mounted upon the lever near the angle between the body portion of the lever and the foot, said angle preferably being rounded as indicated at 13 to form a 35 fulcrum or bearing element upon which the tool may be rocked. The pivot 14 of the claw head is preferably carried by a spring tongue 15 attached as at 16 to the lever and adapted to extend through the 40 shank 17 of the claw head and engage a suitable opening 18 in the lever, said tongue affording a means of holding the pin in place and of permitting the withdrawal of the pin to release or disengage the claw head.

45 The claw head is provided at one end with a nail or spike claw 19 and at the other end with a poll 20 having a shouldered inner side as shown at 21 adapted for engagement over the edge of a board or strip to permit 50 of applying a pulling strain transversely upon the board with relation to a scantling or

stud to which it may be nailed or spiked, the foot 11 forming a bearing upon the surface of the board and extended transversely thereof as a means of preventing the board from splitting. For wide boards the foot may be provided with an extension 11^a consisting of a channeled bar fitted over the foot 11 and secured thereto by a bolt 22 engaging registering openings 23 and 24 formed respectively in the foot 11 and the extension 11^a. 65

In removing boards of frame timber they may be started for example by placing the inner edge of the foot against the inner surface of the board or the surface thereof 70 which is away from the operator, hooking said foot over the edge of the board, in other words placing the outer surface of the head against the timber or scantling and then drawing upward upon the handle end 75 of the lever, after which the poll end of the claw head may be engaged over the edge of the board with the outer edge of the foot in contact with the surface of the board toward the operator whereupon a downward pressure applied to the handle end of the lever 80 will serve to draw the board away from the studding while the buckling or splitting of the board is prevented by the pressure of the foot. 85

In this way the board may be removed from the scantling or may be removed sufficiently to permit of forcing it back toward the studding to expose the heads of the securing nails or spikes to permit of engagement thereof by the claw 19 on the head whereupon such nails or spikes may be completely withdrawn to release the board. 90

Having described the invention, what is claimed as new and useful is:— 95

1. A tool for the purpose indicated having a lever forming at one end a handle and provided at the other end with a transversely extending bearing foot, and a claw head pivotally mounted for swinging movement upon the lever adjacent to the angle between the body portion thereof and said foot. 100

2. A tool for the purpose indicated having a lever forming at one end a handle and provided at the other end with a transversely extending bearing foot, and a claw head pivotally mounted for swinging movement upon the lever adjacent to the angle between the body portion thereof and said foot, a channeled foot extension being detachably engaged with said foot. 105

3. A tool for the purpose indicated having

a lever forming at one end a handle and provided at the other end with a transversely extending bearing foot, and a claw head pivotally mounted for swinging movement upon the lever adjacent to the angle between the body portion thereof and said foot, the claw head having a poll end provided with an inner abrupt shoulder for engaging a board interposed between the same and the outer 10 surface of the foot.

4. A tool for the purpose indicated having a lever forming at one end a handle and provided at the other end with a transversely extending bearing foot, and a claw head pivotally mounted for swinging movement upon the lever adjacent to the angle between the body portion thereof and said foot, the angle 15 between the body portion and foot of the lever being rounded to form a fulcrum or 20 rocking bearing.

5. A tool for the purpose indicated having a lever forming at one end a handle and provided at the other end with a transversely extending bearing foot, and a claw head piv-

otally mounted for swinging movement upon 25 the lever adjacent to the angle between the body portion thereof and said foot, the angle between the body portion and foot of the lever being rounded to form a fulcrum or 30 rocking bearing and the head being provided with a pulling shoulder opposed to said fulcrum or bearing.

6. A tool for the purpose indicated having a lever forming at one end a handle and provided at the other end with a transversely extending bearing foot, and a claw head pivotally mounted for swinging movement upon the lever adjacent to the angle between the body portion thereof and said foot, said head having a shank provided with a pivot pin 35 opening, and the pivot pin being carried by a spring tongue secured to the lever, for yieldingly holding the pin in head engaging position.

In testimony whereof he affixes his 45 signature.

JOHN M. PEDERSON.
